UNITED STATES PATENT OFFICE.

GEORGE SNYDER, OF PHILADELPHIA, PENNSYLVANIA.

IMPROVED COMBINATION OF THE STROP AND HONE.

Specification forming part of Letters Patent No. 39,362, dated July 28, 1863.

To all whom it may concern:

Be it known that I, GEORGE SNYDER, of Philadelphia, Pennsylvania, have invented a Combined Hone and Strop and Case for the Same; and I do hereby declare the following to be a full, clear, and exact description of the same, reference being had to the accompanying drawings, and to the letters of reference marked thereon.

My invention consists of a hone, strop, and case constructed and arranged in the manner described hereinafter, the whole forming a new and useful article of manufacture.

In order to enable others to make my invention, I will now proceed to describe its construction and operation.

On reference to the accompanying drawings, which form a part of this specification, Figure 1 is a side view of my combined hone and strop and case for the same; Fig. 2, a longitudinal section; Fig. 3, a transverse section on the line 1,2, Fig. 2, and Fig. 4 a perspective view.

Similar letters refer to similar parts throughout the several views.

A is a suitably-formed block of wood, in the upper surface of which is set the hone B, one end, a, of the block being so shaped as to form a handle to be grasped by the hand.

C is a lid, recessed in the under side, and hinged at b to one end of the block A, the lid when down covering the face of the block and inclosing the hone. To the upper surface of the lid C is cemented a strip, e, of leather properly prepared for being used as a strop.

D is a casing of stiff paper, leather, or other suitable material, and is divided longitudinally by the partition e into two compartments, the larger of which is of such a size as to contain the block A and lid C when the lat-

ter is depressed, the upper compartments, G, being of proper dimension, to receive one or two razors, the end of this compartment being closed by a flap, d, as best observed on reference to Figs. 2 and 4.

When the razor has to be applied to the hone the latter is exposed by throwing the lid C back.

After the razor has been sharpened on the hone B, the lid C is turned down to the position shown in Fig. 2, and the leather covering the top surface of the same used as a strop.

The advantage of combining the block A, hone B, lid C, and strip of leather e will be apparent, the strop being always at hand ready for use and resting on a solid and steady base.

The case D, which may be considered a necessary adjunct to—in fact, an essential part of the combined hone and strop—contributes its advantages, as it has a compartment for the reception of a razor or razors, the whole contrivance being simple and compact and especially well adapted for use in the army and for travelers.

I claim as my invention and desire to secure by Letters Patent—

As a new article of manufacture, the block A, hone B, lid C, and strop e, with a case, D, the whole being constructed and arranged as and for the purpose described.

In testimony whereof I have signed my name to this specification in the presence of two subscribing witnesses.

GEO. SNYDER.
